UNITED STATES PATENT OFFICE.

LESTER REYNOLDS, OF YREKA, CALIFORNIA, ASSIGNOR OF ONE-HALF TO
FRANCIS RILEY, OF SAME PLACE.

GRAIN SCALE AND REGISTER.

SPECIFICATION forming part of Letters Patent No. 376,044, dated January 3, 1888.

Application filed July 25, 1887. Serial No. 245,207. (No model.)

To all whom it may concern:

Be it known that I, LESTER REYNOLDS, a citizen of the United States, residing at Yreka, in the county of Siskiyou and State of California, have invented certain new and useful Improvements in Grain-Weighers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 Figure 1 is a front elevation of the machine. Fig. 2 is a side elevation of the same. Fig. 3 is a vertical longitudinal section on line $x-x$, Fig. 2. Fig. 4 is a transverse vertical section on line $y-y$, Fig. 1. Fig. 5 is a vertical section 20 on line $z-z$, Fig. 2, showing the registering-wheels. Fig. 6 is a horizontal section on line $x-x$, Fig. 1. Fig. 7 is a sectional detail side view showing one of the scale mechanisms as set and sprung in dotted lines.

25 This invention relates to improvements in automatic weighing-machines; and it has for its objects to provide a machine in which the grain or other material is weighed and delivered from the scale-bin automatically, and in 30 which the movements of the scale-bin actuate suitable mechanisms for registering the number of times the bin has been filled, so that the amount of material passed through the machine can be accurately determined.

35 To these ends the invention consists in the novel construction and arrangement of parts hereinafter described, illustrated in the drawings, and particularly specified in the appended claims.

40 Referring to the drawings by letter, A designates a casing in which I preferably mount my weighing and registering mechanisms. This casing is of general rectangular shape and stands upon one end, and has its top end 45 provided with a hopper, a , through which the material is fed into the machine. The top is preferably hinged, so that it can be raised to permit access to the interior of the casing.

a' designates the front hinged door of the 50 casing, hereinafter referred to.

In the interior upper portion of the casing A is mounted the scale-bin B. This bin is divided into two hoppers, b b' , by a central vertical partition, b^2 , and each hopper has a downwardly and outwardly inclined bottom, b^3 , the upper ends of which meet below partition b^2 and form a close joint therewith and with each other. At the lower ends of bottoms b^3 the outer sides of the hoppers are cut away, forming openings b^4 , through which the grain is delivered from the hopper onto a double-inclined chute, C, which has its apex vertically below the central partition of the bin, and which is adapted to conduct the material delivered from the bins to the opposite sides of 65 the same and deliver it into any proper receptacle or delivery spout or pipe.

D designates a horizontal shaft mounted in suitable bearings in the rear wall of casing A and in a front vertical partition or standard, 70 A'. Above the chutes C on this rod the bin B is mounted, at the junction of its bottoms and central partition, in suitable manner, so that the bin, which is of less width than the interior of the casing, can oscillate freely on 75 said shaft D.

d d designate outstanding lugs or arms secured to the opposite sides of the bin, and which are adapted to play through vertical slots a^2 , formed in the side walls of the casing 80 A, when the bin is suitably oscillated. These lugs engage the weighing mechanisms, one of which is located on each side of the machine, and are similar in construction and operation. They are constructed as follows:

85 E E designate rectangular frames secured to the upper portions of the sides of casing A.

F F designate horizontal beam-arms pivoted at their rear ends to the side rails of frames E. The arms F are formed with two 90 converging arms, $f-f$, on their upper sides, which do not, however, meet.

G G designate vertical latch-headed rods or bars composed of two similar pieces, $g-g$, having an integral head, g' , rising from beams F, 95 and embracing the beams centrally between the arms $f-f$ by their pieces g , as shown. The outer ends of the beams F are provided with the usual scale-marks and weights, and are kept from sidewise swinging by means of ver- 100

tically-slotted pieces f^2 , as shown. The upper ends of rods G stand opposite openings a^2 , and are guided laterally by slotted pieces a^3 , which are set so that the heads of bars G will be kept 5 in proper position for engagement of arm d of the bin.

$f^4 f^4$ designate suitable springs adapted to hold rods G in proper position.

H H designate flat bars lying between the 10 pieces g g of bars G, and extending from the head g thereof down to and between the arms f f of beams F. The bars H are pivoted centrally of their length to the bars G, as shown, and oscillate laterally on their pivots.

15 The operation of this part of the apparatus is as follows: The bin B is turned to one side, so that the arm d on that side will engage the hooked head g' of rod G of its corresponding weighing mechanism. When in such position, 20 the mouth of the hopper is closed by abutting against a suitable piece, B', secured to the inner sides of casing A, so that as long as the bin is inclined toward that side its mouth is closed. There are similar pieces B' for each 25 hopper b b' of the bin. The weights on the scale-beams are then properly set and material is fed into the bin through hopper a. This hopper has its mouth contracted, so that the oscillations of the bin will turn its partition b^2 to either side of the hopper-mouth, and material entering the bin therefrom will be directed by the partition into either hopper b or b', according to the position of the bin, the hopper being filled always being the highest 30 one, relatively, and opposite that engaged by its arm d with the weighing mechanism. Now, when the hopper is filled sufficiently to balance the weight on the scale-beam F, to which the bin is engaged, as described, the bin 35 is oscillated on shaft D, and it begins to lift the beam F through its described connections. This lifting of beam F causes its outer arm, f, to engage the lower end of bar H and oscillate it on its pivot, forcing its upper end outward, 40 and thereby engaging the arm d , and causing the bar G to disengage its head therefrom, and immediately upon the disengagement of arm d and head g' the bin is forcibly oscillated to the other side of the casing by the weight of 45 the grain in the hopper of the bin, and the arm d on that side is engaged with the weighing mechanism and operated by the filling of the opposite hopper of the bin, which is then in position to receive grain from hopper a. 50 As the bin is oscillated the mouths of its hoppers are freed from pieces B', and the material can escape freely into chute C. The weighing mechanisms are preferably protected by hinged doors e on frames E. After the release 55 of the bin the return of beam F to its normal position by its weight will also cause the lever H, by the opposite arm, f, of the beam, to be returned to its normal position, as is evident.

60 65 I will now describe the registering devices. To the outer side of partition A', and jour-

naled by its shaft i in suitable bearings in said partition, and a similar partition, A², or other support outside of partition A', is a large ratchet-wheel, I, the upper periphery of which 70 extends slightly above the shaft D.

J is a small gear-wheel on the shaft of wheel I, and rigid with the latter, so that they turn simultaneously. The teeth of wheel I are preferably one hundred in number. The gear-wheel J engages with the teeth of a large gear-wheel, K, suitably mounted below the same on a shaft k, the relative sizes of the wheels J and K being such that the former makes ten revolutions to one of the latter. 80

L designates a pawl engaging wheel I, which pawl is mounted on a stud or pin, l, secured to the side of bin B, and playing through a suitable slot in partition A'. The pin l is set at such a distance from shaft D that its movement, and consequent movement of pawl L, owing to the oscillations of bin B, will only actuate wheel I one notch, so that said wheel is moved one notch for every filling of both hoppers b b' of bin B. 90

M designates a suitable brake-pad hinged above wheel I and controlled by a spring, m, as shown, serving to prevent undue rotation of wheel I.

N designates a suitable dial-plate placed 95 outside wheels I K on partition A², and having dials n n' for the respective wheels I K.

O designates an index-arm on the extended shaft i of wheel I, and o an index-arm on the shaft of wheel K. The dial N of wheel I is divided into units up to one hundred, so that fractions of a hundred filling of the bin can be ascertained, and the dial n' is divided into hundreds up to a thousand, so that at a glance any number of times that the bin has been 105 filled and emptied up to one thousand can be ascertained, and by multiplying such number by the added weights of the two weighing-beams F the total weight of material passed through the bin can be ascertained. The dials 110 n' are protected by the door a' of the casing.

Having thus described my invention, what I claim as new, and desire to secure by Letters Patent, is—

1. The combination, with an oscillating grain-holding bin having an outstanding arm, of a scale mechanism for engaging the arm of the bin, composed of a horizontal scale-beam, F, having arms f f, the hook-headed bar G, pivoted to beam F, and the lever-bar H, pivoted to bar G and actuated by the arms f upon the lifting of beam F to cause the disengagement of bar G and the arm of the bin, as described. 115

2. The combination, with a suitable supporting-easing, of an oscillating bin, B, having hoppers b b', mounted on a transverse shaft, D, arms d d on opposite sides of said bin playing through openings in the sides of the casing, and scale mechanisms on each side 120 of the bin adapted to automatically engage and release the bin as it oscillates, each com- 125

posed of the scale-beams F, having arms f f, spring-controlled hook-bar G, and pivoted lever-bar H, all constructed and operating as described.

5 3. The combination of the oscillating bin B, having vertical partition b² and inclined bottoms b³, mounted on a transverse shaft, and a hopper, a, adapted to deliver grain to the bin, with the scale mechanisms composed of beams F, rods G, and levers H and their connections, and the registering mechanisms composed of wheels I, J, and K and their connections operated by the oscillations of the bin, all constructed, arranged, and operating substantially for the purpose set forth.

10 4. The combination of casing A, having hopper a and chute C, the oscillating bin B, having hoppers b b', the pieces B', secured to the casing and closing the mouths of the hoppers

b b', and the arms d d, with the scale mechanisms inclosed in frames E E on the sides of the casing, and each composed of beams F, having arms f f, rod G, having head g for engaging the arms d, and lever H, pivoted to rods G and controlled by arms f, the springs f¹, 25 and pieces f and f², and the registering mechanism composed of wheels I, J, and K and their index arms and dials, and the actuating-pawl L on the bin and brake M, all constructed, arranged, and operating substantially as de- 30 scribed.

In testimony whereof I affix my signature in presence of two witnesses.

LESTER REYNOLDS.
